RUBBING MACHINE

Gustaf H. Ekstrom, Rockford, Ill., assignor to
 Sundstrand Machine Tool Co., Rockford, Ill.,
 a corporation of Illinois

Application November 6, 1937, Serial No. 173,264

5 Claims. (Cl. 121—3)

The invention relates generally to a rubbing machine and more particularly to a rubbing machine of the pneumatically actuated type.

A general object of the invention is to provide a rubbing machine of new and improved construction rendering the machine unusually light to facilitate handling thereof.

Another object of the invention is to perfect a pneumatically actuated rubbing machine of new and improved construction which is unusually light and yet is free from vibration.

A further object is to provide a rubbing machine so constructed that the reactions of the pistons and of the rubbing shoes or pads are balanced and opposed so that they are counteracted to eliminate vibration and turning of the rubbing machine.

Yet another object is to perfect a pneumatically actuated rubbing machine having a pair of pistons disposed in a line and each actuating a rubbing shoe with the shoes disposed parallel with one another and side by side, and with the pistons and shoes moving in opposite directions so as to counterbalance the forces acting on the pistons and on the shoes.

Other objects and advantages will become apparent from the following detailed description taken in connection with the accompanying drawing, in which:

Fig. 1 is a vertical longitudinal sectional view of the body of a rubbing machine embodying the features of the invention.

Fig. 2 is a top plan view of the machine shown in Fig. 1, partially in section along the line 2—2 of Fig. 1, better to show the valve and valve ports.

Fig. 3 is a transverse sectional view taken along the line 3—3 of Fig. 1.

Fig. 4 is a view taken along the line 4—4 of Fig. 3, looking in the direction of the arrows.

While the invention is susceptible of various modifications and alternative constructions, it is shown in the drawing and will be described hereinafter in a preferred embodiment, but it is not intended that the invention is to be limited thereby to the specific construction disclosed, but it is intended to cover all modifications and alternative constructions falling within the spirit and scope of the invention as defined by the appended claims.

As shown in the drawing for purposes of disclosure, the rubbing machine comprises generally a body 10, constituting a housing for motor means and valve means, and a pair of rubbing

shoes 11 slidably supported beneath the body and adapted to be actuated by the motor means. The body 10 is composed of an elongated casting 12 of some light weight material, preferably 5 aluminum, and, as best seen in Fig. 3, has in transverse cross section a cylindrical intermediate portion 13, a flat base portion 14, and a top portion 15 having bulging sides 16, preferably hollow, which serve as a grip for handling the 10 rubbing machine. The cylindrical intermediate portion 13 of the casting 12, which may be formed by boring from end to end of the casting 12, has a sleeve 17 fitted therein which sleeve also extends from end to end of the casting. This 15 sleeve forms the cylinders of the motor means and in order that there may be two motor means a circular plug 18 preferably of brass is pressed into the sleeve and positioned centrally thereof. To complete the cylinders, the external ends 20 thereof are closed by means of a cap 19 and a cap 20 suitably secured as by bolting to the ends of the casting 12.

Reciprocable in each of the cylinders thus formed within the casting 12 is a piston 23 having 25 a piston ring 24 at each end so as to make the piston double acting. Preferably each piston is also cut away intermediate its ends as at 25 to reduce the amount of material in the piston and hence the weight thereof. It is to be noted 30 from the foregoing that the pistons are in line and, moreover, are on the horizontal center and substantially on the vertical center of the machine.

Each of the pistons 23 is adapted to actuate 35 a rubbing shoe 11 which shoes herein are disposed side by side and parallel with one another. Accordingly there is secured to the bottom or base 14 of the casting 12 a bearing plate 27 having serrations 28 extending longitudinally thereof. 40 This plate may be removably secured to the base 14 as by screws 29 (see Fig. 4). Slidable on the bearing plate 27 and having complementary serrations are two L-shaped slides 30 (see Fig. 4) disposed in reversed position so that the longitudinal legs are disposed opposite one another. Each of the slides 30 is secured to one of the 45 pistons 23 by means of a pin 31 fixed diametrically of the piston centrally thereof and having one end projecting through an elongated slot 32 formed for that purpose in the bottom of the sleeve 17 and the base portion 14 of the casting 12 and a slot 32' formed in the bearing plate 27. The projecting end of the pin 31 is made 50 fast to the slide 30 so that the slide will be re-

tained on the bearing plate 27 and will be reciprocated with the piston 23 as the latter reciprocates in its cylinder. Side gibbs 33 further aid in guiding and retaining the slides 30 on the bearing plate 27.

Secured to each slide 30 is one of the rubbing shoes 11 and to that end each slide is formed with a block 35 to which a shoe 11 may be removably secured as by screws 36. The shoes in turn in conventional manner carry a pad 37, usually of rubber, and a felt pad 38 over which a strip of sandpaper 39 is mounted. Herein the sandpaper is secured simply by folding the same inwardly over the ends of the shoe 11 and securing the ends of the strip beneath a spring member 40 terminating in teeth 41. The spring member 40 is riveted at its inner end to the shoe 11 and in order to add to the strength thereof has superimposed on it a second leaf spring 42.

In order to effect reciprocation of the pistons 23 by the application of pneumatic pressure, the body of the rubbing machine is provided with suitable passages for the supply and exhaust of air and with a valve mechanism generally designated 45 controlling the supply and exhaust of the air to and from opposite ends of the cylinders in timed relation with the reciprocation of the pistons, in order to effect continuous operation of the machine. To that end the casting 12 is provided in its top portion 15 with a valve chamber 46 and mounted in the chamber is a valve 47. Preferably, to insure a better seal, the valve 47 operates in an annular valve sleeve 48 which, as best seen in Fig. 2, is provided with six radial ports P1, P2, P3, P4, P5 and P6. Of these, ports P1 and P2 are exhaust ports and communicate respectively with exhaust passages 49 and 50 extending longitudinally centrally of the portion 15 and opening through the ends of the casting 12. The passages 49 and 50 are continued as 49' and 50', respectively, in the end caps 20 and 19 and are directed downwardly so as to discharge onto the surface being rubbed or polished so as to aid in keeping the surface clean. Ports P3 and P4 serve alternately as inlet and exhaust ports and communicate respectively (see Fig. 2) with passages 51 and 52 extending parallel with the passages 49 and 50 on opposite sides thereof and leading by means of inclined passages 51' and 52' respectively to the outer ends of the cylinders in which the pistons 23 reciprocate. Like passages 49 and 50, passages 51 and 52 are readily formed by drilling through the ends of the casting 12 with the ends of the passages opening through the ends of the casting 12 blocked by the caps 19 and 20. Ports P5 and P6 also serve alternately as inlet and exhaust ports and communicate respectively through short horizontal ducts with vertical passages 53 and 54 leading to the inner ends of the cylinders. The casting 12 is formed with yet another passage 55 extending parallel with the passage 50 on the opposite side from the passage 52 and this passage 55 constitutes an air supply passage. To that end it opens through the end of the casting 12 and registers with a passage 56 in the cap 19 which terminates in a large port 57 threaded for the reception of an air hose. At its inner end the passage 55 extends upwardly and opens into the valve chamber 46 above the valve 47 therein.

In order suitably to distribute the air supplied through the passage 55, the valve 47 is formed with two vertical passages 60, opening through the top of the valve so as to communicate with the valve chamber 46 and the supply

passage 55, which passages terminate at their lower ends in radial ports 61 disposed diametrically opposite one another. The valve 47 is also undercut externally on diametrically opposite sides and on sides between the ports 61 with slots 62 of sufficient length to embrace two adjacent ports. From the foregoing description, it will be apparent that by oscillating the valve 47 the ports 61 may be made to register with the ports P5 and P6 for supplying air under pressure to the inner ends of the cylinders 23, while at the same time the slots 62 will bridge the ports P1 and P3 and P2 and P4 to connect the opposite ends of the cylinders to exhaust, while oscillation of the valve in the opposite direction will cause ports 61 to register with the ports P3 and P4 whereby air under pressure will be supplied to the outer ends of the pistons 23, while ports P5 and P6 will be connected respectively with exhaust ports P2 and P1. To facilitate insertion of the valve 47 in the valve bushing 48, the valve chamber 46 opens through the top of the casting 12 and is closed by a suitable plug 63.

To oscillate the valve 47 for causing the ports 61 to register alternately with the ports P3 and P4 and P5 and P6 in timed relation with the reciprocation of the pistons 23, the lower end of the valve is cleft to receive the rectangular end of a wiggler stem 65 rotatably journaled in a bore drilled vertically through the plug 18 as well as through the sleeve 17 and the intermediate cylindrical portion 13 of the casting 12. The lower end of the pin 65 extends into a circular recess 66 formed in the base portion 14. Rotatable in this recess and fixed to the projecting end of the pin 65 is a disk 67 formed with radial and diametrically opposite slots 68 in which are slidable blocks 69 each secured by a pin 70 to one of the slides 30. To accommodate the pins 70 the bearing plate 27 is provided with slots 71. With the blocks 69 free to slide in the slots 68, longitudinal reciprocation of the slides 30 will be converted into oscillatory movement of the pin 65 and the valve 47 thereby effecting the supply of air under pressure alternately to opposite ends of the pistons 23 to effect continuous reciprocation thereof. The sides of the cleft in the lower end of the valve are not parallel but are diverging from the center of the valve so as to form with the rectangular end of the wiggler stem a lost motion connection. This connection enables the pistons 23 to travel through a portion of their stroke while the valve remains stationary with the ports in a particular registry, and as the pistons approach the end of their stroke in that direction the valve is suddenly rotated to effect an opposite registry of the ports whereby movement of the pistons in the opposite direction is initiated.

It will be apparent from the foregoing that I have provided first of all a rubbing machine which is unusually light in that it has an aluminum body and a minimum number of cylinders and other operating parts. The rubbing machine is also quickly and economically constructed since a majority of the air passages may be formed by drilling and, similarly, the bore in which the cylinder sleeve 17 is received may be drilled. Moreover, of greatest importance is the arrangement and location of the pistons and the rubbing shoes and their mode of operation whereby the rubbing machine, though extremely light, is unusually free from vibration and from a tendency to rotate on the work being surfaced. Contributing largely to that feature is the con-

struction whereby the pistons 23 are alined, and the mode of operation of the pistons, with the result that the forces and reactions on the pistons are opposed so as to counterbalance one another. Similarly, the parallel arrangement of the shoes 11 with the motion in opposite directions also contributes to the stability of the machine.

I claim as my invention:

1. A rubbing machine of the character described having, in combination, pneumatic motor means comprising a body composed of an elongated casting having a longitudinally extending bore formed therein, a cap secured over each end of said casting to close the outer ends of the bore, one of said end caps having a port for the reception of an actuating medium supply conduit, a transverse partition intermediate the ends of said casting dividing the bore into two alined cylinders of equal length, a piston reciprocable in each of the cylinders, and means for supplying and directing actuating medium to said cylinders comprising a valve chamber formed in the upper portion of said casting, passages formed in the upper portion of said casting leading from said valve chamber to both ends of both cylinders and to the port for the reception of an actuating medium supply conduit, passages leading from said valve chamber to atmosphere formed partly in the upper portion of said casting and partly in said end caps, a cylindrical valve in said valve chamber oscillatable to various positions to cause the simultaneous discharge of actuating medium alternately to the inner and outer ends of both cylinders to effect simultaneous reciprocation of the pistons either inwardly toward or outwardly away from said partition, and means actuated in timed relation with the reciprocation of said piston including a pin extending through said partition and at its upper end having a lost motion engagement with said valve to oscillate the same.

2. A rubbing machine of the character described having a pneumatic motor comprising a body composed of an elongated casting having a bore extending longitudinally thereof and opening through both ends thereof, a sleeve fitted in said bore and a cap secured over each end of said casting to close the outer ends of the bore, one of said end caps having a port for the reception of an actuating medium supply conduit, a plug fitted in the sleeve intermediate its ends to form of the sleeve two alined and independent cylinders, a piston reciprocable in each of the cylinders, and means for supplying and directing the actuating medium to said cylinders comprising a valve chamber formed in said casting, a valve oscillatable in said chamber, a supply passage formed in said casting opening at one end to said valve chamber and communicating at the other end with the port in one of the end caps, passages leading from said valve chamber to the inner and the outer ends of said cylinders and exhaust passages leading from said valve chamber to atmosphere, said valve being ported in one position to connect the supply passage with the passages leading to the inner ends of both cylinders while the outer ends of both cylinders are connected to the exhaust passages and in another position connect the supply passage with the passages leading to the outer ends of both cylinders while the inner ends are connected to the exhaust passages, to effect reciprocation of the pistons in opposite direc-

tions, and means for oscillating the valve in timed relation with the reciprocation of said pistons.

3. In a rubbing machine of the character described, a pneumatic motor means comprising an elongated casting forming a housing having in transverse cross section a cylindrical intermediate portion and a hollow top portion with sides bulging laterally beyond the intermediate portion to constitute a grip for holding the machine, a cylindrical sleeve extending longitudinally of said intermediate cylindrical portion from end to end of the casting, a cap secured over each end of the casting for closing the ends of said sleeve, a circular plug disposed in said sleeve midway between the ends thereof to divide the sleeve into two longitudinally extending and axially alined cylinders of equal length, a piston reciprocable in each of said cylinders so formed, and means for controlling the supply of actuating medium to said cylinders comprising a valve chamber formed in the upper portion of said casting, passages leading from said valve chamber to both ends of both cylinders, to the atmosphere, and to a supply conduit for actuating medium, a cylindrical valve in said valve chamber oscillatable to various positions to cause the simultaneous discharge of actuating medium alternately to the inner and the outer ends of both cylinders to effect simultaneous reciprocation of the pistons either inwardly toward or outwardly from the plug, and means actuated in timed relation with the reciprocation of said piston including a wiggler pin extending through said plug and at its upper end engaging said valve to oscillate the same.

4. A rubbing machine of the character described having, in combination, pneumatic motor means comprising a body composed of an elongated casting having a longitudinally extending bore formed therein, a cap secured over each end of said casting to close the outer ends of the bore, a transverse partition intermediate the ends of said casting dividing the bore into two aligned cylinders of equal length, a piston reciprocable in each of the cylinders, and means for supplying and directing actuating medium to said cylinders comprising a valve chamber formed in the upper portion of said casting, passages formed in the upper portion of said casting leading from said valve chamber to both ends of both cylinders and to a supply port, passages leading from said valve chamber to atmosphere, a valve in said valve chamber oscillatable to various positions to cause the simultaneous discharge of actuating medium alternately to the inner and outer ends of both cylinders to effect simultaneous reciprocation of the pistons either inwardly toward or outwardly away from said partition, and means actuated in timed relation with the reciprocation of said pistons having engagement with said valve to oscillate the same.

5. In a rubbing machine of the character described, a pneumatic motor means comprising an elongated casting forming a housing having in transverse cross section a cylindrical intermediate portion and a hollow top portion with sides bulging laterally beyond the intermediate portion to constitute a grip for holding the machine, a cylindrical bore extending longitudinally of said intermediate cylindrical portion from end to end of the casting, a cap secured over each end of the casting for closing the ends of said bore, a wall disposed transversely of said bore midway be-

tween the ends thereof to divide the bore into two longitudinally extending and axially aligned cylinders of equal length, a piston reciprocable in each of said cylinders so formed, and means for controlling the supply of actuating medium to said cylinders comprising a valve chamber formed in the upper portion of said casting, passages leading from said valve chamber to both ends of both cylinders, to the atmosphere, and to a supply conduit for actuating medium, a valve in said valve chamber oscillatable to various positions

5 to cause the simultaneous discharge of actuating medium alternately to the inner and the outer ends of both cylinders to effect simultaneous reciprocation of the pistons either inwardly toward or outwardly from said wall, and means actuated in timed relation with the reciprocation of said pistons including a member extending through said wall and at its upper end engaging said valve to oscillate the same.

10
